(57) **CLAIM**

The ornamental design for a folding tray table, as shown and described.

DESCRIPTION

FIG. 1 is a perspective view of a folding tray table, showing my new design;

FIG. 2 is the second perspective view thereof;

FIG. 3 is the third perspective view thereof;

FIG. 4 is a front elevational view thereof;

FIG. 5 is a rear elevational view thereof;

FIG. 6 is a left elevational view thereof;

FIG. 7 is a right elevational view thereof;

FIG. 8 is a top plan view thereof;

FIG. 9 is a bottom plan view thereof;

FIG. 10 is a partial enlarged view of FIG. 2;

FIG. 11 is a partial enlarged view of FIG. 2;

FIG. 12 is a partial enlarged view of FIG. 3;

FIG. 13 is a partial enlarged view of FIG. 3;

FIG. 14 is a perspective view of the folding tray table in a folded state; and,

FIG. 15 is a partial enlarged view of FIG. 14.

The broken lines in the figures are for the purposes of illustrating portions of the folding tray table, which form no part of the claimed design.
